UNITED STATES PATENT OFFICE.

ALBERT F. JONES, OF SALEM, MASSACHUSETTS.

STONE-DRESSING MACHINE.

SPECIFICATION forming part of Letters Patent No. 659,478, dated October 9, 1900.

Application filed September 18, 1899. Serial No. 730,715. (No model.)

To all whom it may concern:

Be it known that I, ALBERT F. JONES, of Salem, county of Essex, and State of Massachusetts, have invented an Improvement in Stone-Dressing Machines, of which the following description, in connection with the accompanying drawings, is a specification, like letters on the drawings representing like parts.

This invention relates to stone-dressing machines, and has for its object to construct a machine having the capability of cutting a stone from the edge inward toward the center instead of cutting in parallel lines, as usual, yet said machine also has the capability of cutting in parallel lines.

When beginning to cut the surface of a rough stone, I find in practice that each cut should be made from the edge inward and that the operation should continue in this manner until the surface all around the stone has been cut in, say, two or more inches from the edge, and then the operation may continue in this manner or may continue by cutting in parallel lines. By cutting the surface from the edge inwardly I find that all danger of chipping off the stone at the corners is obviated.

The machine embodying this invention comprises, essentially, a main frame, a truck adapted to support the stone which travels transversely with relation to the main frame and is adapted to be held fixed in any position that it may be set, and a tool-carriage mounted on the frame which is adapted to travel lengthwise the frame at right angles to the movement of the truck and is also adapted to be held fixed in any position that it may be set. The traveling tool-carriage bears the tool or tools, (a pointing-tool and a bushing-tool being preferably employed,) and means are provided for vibrating said tool or tools, which is also borne by the traveling carriage, so that either or both of said tools may be vibrated continuously regardless of the position of the carriage and also regardless of whether the carriage is moving or is held at rest. Means are also provided for holding the pointing-tool at an oblique angle to a horizontal plane and also for varying the obliquity of said angle, and means are also provided for bodily adjusting the tool in

the arc of a circle about a vertical axis in order that it may be turned at the corners of the stone and brought into correct position to continue its cutting operation, said means being such that said tool may be bodily turned to occupy any position of a complete cycle. Means are also provided for adjusting said tool or tools to different elevations, and means are also provided for varying the thrust of the tool, and all of the aforesaid adjustments are of such character that they may be made while the tool is vibrating and the machine is in operation.

Figure 1 shows in front elevation a stone-dressing machine embodying this invention; Fig. 2, a plan view of the machine shown in Fig. 1; Fig. 3, an enlarged detail showing the turret and two tools borne by it; Fig. 4, a vertical sectional detail of the turret, showing particularly the means for adjusting it on its vertical axis and also means for adjusting it to different elevations; Fig. 5, a cross-section of the turret shown in Fig. 4, taken on the dotted line $x-x$; Fig. 6, a vertical sectional detail of the bushing-tool, its holder, and support; Figs. 7, 8, and 9, details of the pointing-tool and its sliding tool-holder; Fig. 10, a detail showing in section the support for the pointing-tool holder and also showing the means for operating said tool-holder; Fig. 11, a vertical section of the bushing-tool; Fig. 12, a detail of the bushing-tool to be referred to; Fig. 13, a detail showing means for connecting the bushing-tool with the turret; Fig. 14, an under side view of the pointing-tool, its holder, and support; and Fig. 15, a diagram showing the top surface of a stone and arrows which represent the cutting-tool and also other arrows which represent the direction of travel.

The main supporting-frame of the machine, as herein shown, consists, essentially, of horizontal side and end bars a , rigidly secured together to form a rectangular frame, a number of upright bars or corner-posts a' , rigidly secured to said rectangular frame, and horizontal side and end bars a^2 , rigidly secured together and to the upper ends of said upright bars or corner-posts a' , and additional cross-bars will be provided as required to serve as braces and also as bearings or sup-

ports for some of the operating parts, yet said supporting - frame may be otherwise constructed.

A stone to be dressed or otherwise operated upon is placed upon any suitably-constructed platform car or truck *b*, (see Fig. 1,) which is herein represented as composed, essentially, of a platform or table *b'*, upon which the stone is placed, having bearings *b²* upon its under side which receive and support axles *b³*, two in number, which bear at their outer ends flanged wheels *b⁴*. This truck *b* is movable transversely with relation to the main frame and is adapted to be held at rest in any transverse position relative thereto and is also adapted to be moved constantly in either direction, and in order that said truck may thus be moved transversely two parallel rails *b⁵* are employed on which the flanged wheels *b⁴* run, said rails being secured upon cross-bars *b⁶* and *b⁶⁰*, the former extending from side to side of the machine and rigidly secured to the front and back longitudinal bars *a* and the latter extending for any suitable distance outside of or beyond one of said bars *a*. Provision is thus made whereby the truck may be moved transversely relatively to the frame and also moved along to any suitable track which may be provided for it.

When the truck *b* is placed in position for the tools to operate upon the stone, it is desirable to hold the truck securely in whatever position it may be set in order that the tools borne by a suitable carriage to be described may travel over it and act upon the stone, yet it is also desirable to provide for moving the truck constantly in either direction, while the carriage bearing the tools remains at rest in order that the tools may also act upon the stone, and to enable these results to be accomplished suitable conveying mechanism is provided for the truck, which, as herein shown, consists of a rack *b⁷*, secured to the under side of the platform *b'* of the truck *b*, which extends lengthwise the truck and is engaged by a pinion *b⁸*, secured to a shaft *b⁹*, having its bearings in the cross-bars *b⁶* and in a cross-bar *a¹⁰* of the frame, and said shaft *b⁹* has secured to it at one end a toothed gear *b¹⁰*, which is engaged by a toothed gear *b¹²*, secured to a shaft *b¹³*, having its bearings in the cross-bar *a¹⁰* and in one of the end bars *a* of the frame, and said frame *b¹³* has secured to it a worm-wheel *b¹⁴*, which is engaged and driven by a worm *b¹⁵*, secured on a shaft *b¹⁶*. The shaft *b¹⁶*, bearing the worm *b¹⁵*, is supported at one end in a bearing-block *b¹⁷*, pivotally connected to a bracket or stand *b¹⁸*, erected upon one of the end bars *a* of the frame, and said shaft *b¹⁶* has secured to it near its opposite end a friction-wheel *b¹⁹*, which is held in position on the shaft *b¹⁶* by a set-screw, whereby it may be adjusted along on said shaft *b¹⁶* as may be desired and held in fixed position wherever it may be set, and said wheel *b¹⁹* occupies a position between a pair of friction

plates or disks *b²⁰* *b²¹*, so that by moving the shaft *b¹⁶* up or down it will be caused to engage the upper or lower plate and be thereby rotated. The front end of the shaft *b¹⁶* has also a bearing in a lever *b²²*, which is pivoted at one end at *b²³* to a bracket or stand *b²⁴*, secured to the bar *a*, and as said lever is moved up and down on its pivot *b²³* the friction-wheel *b¹⁹* will be caused to engage the upper or lower friction plate or disk *b²⁰* *b²¹* or to occupy an intermediate position between said disks. An arm *b²⁵* is secured to the cross-bar *a¹⁰* of the frame, which is formed or provided along one side or edge with three notches, (see Fig. 1,) and said arm is located at one side of and close to the lever *b²²*, so that said lever may engage any one of said notches, according to the position which it is desired it shall occupy, said notched arm thereby holding the lever *b²²* in either one of three different positions.

The disks *b²⁰* *b²¹* are rigidly secured to an upright shaft *b²⁶*, which is rotated continuously by any suitable means, and it will be seen that as said shaft is rotated and the friction-disks *b²⁰* *b²¹* thereby turned the worm-shaft *b¹⁶* will be rotated in one or the other direction, according to which disk *b²⁰* or *b²¹* the friction-wheel *b¹⁹* is engaging, or said worm-shaft *b¹⁶* may remain at rest when the friction-wheel *b¹⁹* occupies an intermediate position between the two disks *b²⁰* *b²¹*, and as the worm-shaft is thus turned in one or the other direction the truck *b* will be moved transversely relative to the frame in one or the other direction. By utilizing worm-gearing as a co-operative part of the operating mechanism for moving the truck *b* it will be seen that said truck *b* will be positively held in whatever position it may be set and also while moving the thrust of the tools will be resisted. By adjusting the friction-wheel *b¹⁹* along on the shaft *b¹⁶*, and consequently toward and from the center of the disks *b²⁰* *b²¹*, the speed of rotation of said shaft *b¹⁶* will be varied. Thus it will be seen that by manipulating the lever *b²²* the truck may be moved constantly in either direction transversely the frame and also may be moved into any desired position and held fixed.

The upright shaft *b²⁶* has its bearings in the main frame and projects above the horizontal bar *a²* of the frame and has a bearing at its upper end in a bracket or stand *b²⁷*, erected on one of the bars *a²*, and said shaft has secured to its upper end a driving-pulley *b²⁸*, over or around which a belt *b²⁹* passes, said belt extending from end to end of the machine and passing around other pulleys to be described and also over or around the pulleys *b³⁰* and *b³¹*, mounted loosely upon a rod or bar supported by brackets or stands *b³²* *b³³*, and also around a main driving-pulley *b³⁴*, held in suitable bearings. The pulley *b²⁸* is therefore driven continuously, and whenever it is desired to move the truck *b* the lever *b²²* will be operated and the friction-wheel *b¹⁹*

moved from its normal intermediate position into engagement with one or the other friction-disk b^{20} or b^{21} . The mechanism thus described for moving the truck b and for positively holding it in whatever position it may be set is simple and efficient; but I do not limit my invention to the employment of this specific mechanism, as it is obvious that other mechanism may be provided whereby the same results may be produced.

The tool or tools which may be employed to operate upon the stone are borne by a carriage which is movable longitudinally or in a direction at right angles to the movement of the truck b , and said carriage, as herein shown, comprises a top plate or table c , made of any suitable shape and size, as shown in Fig. 2, having on its under side hangers c' , which support the axles c^2 , bearing flanged wheels c^3 , which are adapted to run along on rails c^4 , mounted on top of the longitudinal bars a^2 , said rails being made long enough to enable the carriage to move from end to end of the main frame, or substantially so. This longitudinally-movable carriage supports all the tools and the operating mechanism and adjusting devices therefor, and the operating mechanism for the tools is located above the carriage and the tools below it, so that all the various adjustments of the tools may be made without interference.

The longitudinally-movable carriage is adapted to travel constantly in either direction and also to be positively held at rest in whatever position it may be desired, and to accomplish these results suitable conveying mechanism is provided for said carriage, which, as herein shown, consists of a shaft d , having its bearings in hangers d^{25} , projecting from the under side of the carriage and made of suitable length to extend from side to side of the carriage, and pinions d' , secured to each end of said shaft, which rest upon and run along on rack-toothed bars d^2 , secured to the longitudinal bars a^2 , said rack-toothed bars d^2 being made as long as required, and a worm-wheel d^3 is secured to said shaft d , which is engaged and driven by a worm d^4 , (see dotted lines, Fig. 1,) which is secured to an upright shaft d^5 , which passes up through the table c , and said shaft d^5 has secured to its upper end a beveled gear d^6 , which is engaged by a beveled gear d^7 , secured to a horizontal shaft d^8 , disposed obliquely above the table c and projecting toward the center of a pair of friction-disks $d^9 d^{10}$, which are secured to an upright shaft d^{12} , and said shaft d^8 has secured to it a friction-wheel d^{13} , (see dotted lines, Fig. 2,) which is disposed between said friction-disks $d^9 d^{10}$ to be engaged and driven by one or the other of said disks. The friction-wheel d^{13} is secured to the shaft d^8 by a set-screw, so that it may be adjusted along on said shaft toward and from the center of the disks to provide for varying the speed of rotation of said shaft d^8 . The shaft d^8 is adapted to be raised and lowered, so that the

friction-wheel d^{13} will engage either the upper or lower friction-disk $d^9 d^{10}$, and it is also adapted to be held in an intermediate position between said disks, and, as herein shown, a pivoted bearing d^{20} is provided on the table c for the shaft d^8 to provide for such movement. A lever d^{14} is pivoted at one end to a stand d^{15} , and said lever passes between the friction-disks $d^9 d^{10}$ and bears at its opposite or free end a roll which occupies a position in a cam-groove cut or formed in a disk d^{16} , and as said cam-grooved disk d^{16} is turned the lever d^{14} will be caused to occupy either one of three different positions. The lever d^{14} is connected with the shaft d^8 and serves as a means of moving said shaft d^8 in order that the friction-wheel d^{13} , carried by it, may engage one or the other friction-disk $d^9 d^{10}$ or caused to occupy an intermediate position between said disks. The cam-grooved disk d^{16} is rigidly secured to a shaft d^{17} , which has a hand-wheel d^{21} secured to it, which serves as a means of turning it to thereby in turn operate the shaft d^8 . The friction-disks $d^9 d^{10}$ are rigidly secured to an upright shaft d^{12} , to which a belt-pulley d^{18} is secured, and the upper end of said shaft d^{12} has its bearings in an overhanging bracket or stand d^{20} , erected on the table c . The belt-pulley d^{18} is so disposed as to be continuously in engagement with a driving-belt b^{29} and to be moved along with the carriage, yet to continue in engagement with said belt at all times, and consequently the friction-disks $d^9 d^{10}$ will be continuously rotated, yet as the friction-wheel d^{13} has three different positions it will be seen that the shaft d^8 may remain at rest or may be turned in one or the other direction at the will of the operator by manipulating the hand-wheel d^{21} . Thus it will be seen that the carriage may be moved constantly in either direction at will and may be held at rest in any desired position, and by utilizing a worm-wheel and worm as a part of the operating mechanism for moving it the thrust of the tools is resisted. It will also be seen that the operating mechanism for the carriage is borne by the carriage and may be readily thrown into or out of operation at the will of the operator.

On the under side of the movable carriage a turret is located which carries the tool-holders and tools borne by them, and said turret is adapted to be adjusted vertically in order that the tools may occupy different elevations and also adjusted in a rotary direction on its vertical axis, and both of said adjustments are independent of each other, yet capable of operation regardless of the other—that is to say, the turret may be adjusted to different elevations while held in any position of rotary adjustment and may also be adjusted on its vertical axis while held in any position of vertical adjustment. The turret is adapted to be given a complete rotation, so that the tool or tools carried by it may occupy any position in a complete cycle as said turret is revolved. The turret (see Figs. 1 and

4) consists, essentially, of an outer cylinder e' , mounted on and supported by a hollow cylinder e , and said inner cylinder e is stationarily supported, and said outer cylinder e' is adapted to be turned on and relative to said inner cylinder in a rotary direction and also to slide thereon telescopically. The inner cylinder e is formed or provided at its upper end with a flange e^2 , which is bolted or otherwise secured to the under side of the table c of the carriage to thereby hold it stationary. The outer cylinder e' has secured to it a bottom plate e^3 , which is formed or provided on its inner face with a central boss or projection e^4 , which projects up into the inner cylinder, and said boss or projection supports at its upper end in an annular groove provided for the purpose a horizontal plate e^5 , herein shown as made in two parts which are bolted together, (see Fig. 5,) said plate being thus held in position on the boss or projection e^4 , yet providing for rotation of said boss or projection, as will be described. The boss or projection e^4 being formed integral with or secured to the bottom plate e^3 will rise and fall with the outer cylinder e' , and the plate e^5 is moved with it, and to guide said plate e^5 and also assist in guiding the outer cylinder e' splines e^6 are secured to said plate e^5 at opposite sides, which follow in vertical grooves or guideways in plates e^7 , secured to the interior walls of the inner cylinder e . For the purpose of supporting the outer cylinder e' in elevated position and for adjusting it to different elevations two screw-rods $e^8 e^9$ are provided, which extend down into the inner cylinder e through a top plate e^{10} , which is bolted to a flange or ring which is secured to the top of said cylinder e , and the screw-threaded portions of said rods $e^8 e^9$ pass through threaded holes in the plate e^5 , and as said screw-rods are turned in one or the other direction the plate e^5 and outer cylinder e' , connected with it, will be raised and lowered, according to the direction said rods are turned. To turn said screw-rods $e^8 e^9$ simultaneously, and thereby move the outer cylinder e' vertically, they are each provided at their upper ends with a sprocket-wheel $e^{12} e^{13}$, and a single sprocket-chain e^{14} (see Fig. 2) passes around both of said sprocket-wheels and also around a sprocket-wheel e^{15} , which is secured to the upper end of an upright rod or shaft e^{16} , having its bearings in the carriage, and a hand-wheel e^{17} is secured to the lower end of said shaft e^{16} , which serves as a means of turning it. Vertical adjustment is thus accomplished by hand by turning the shaft e^{16} , and thereby turning the two screw-rods $e^8 e^9$ simultaneously, and by such means it will be seen that the outer cylinder e' and parts carried by it will be adjusted at the will of the operator to occupy different elevations. The tools borne by the turret may thus be adjusted to different elevations.

For the purpose of turning the turret on its

vertical axis, whereby the tool or tools borne by it may occupy different positions in the arc of a circle described about said axis, a toothed ring f is secured to the upper end of the outer cylinder e' , which is engaged by a pinion f' , secured to an upright shaft f^2 , and a worm-wheel f^3 is secured to the lower end of said shaft f^2 , which is engaged by a worm f^4 , secured to a horizontal shaft f^5 , having secured to it a hand-wheel f^6 , so that by turning said hand-wheel f^6 the shaft f^2 , bearing the pinion, may be turned, and the outer cylinder e' thereby revolved. The length of the pinion f' is sufficient to provide for vertical adjustment of the outer cylinder. By utilizing a worm and worm-wheel as a co-operative part of the adjusting device it will be seen that said outer cylinder e' may be positively held in whatever position it may be set and the thrust of the tools resisted. The turret, which is adjustable vertically and also adjustable in a rotary direction about its vertical axis, is herein shown as carrying or supporting two different tools—viz., a pointing-tool and a bushing-tool—and said tools are held in suitable tool-holders, which are in turn held by suitable tool-holder supports, which are constructed and arranged to admit of the tools being adjusted relatively to the turret and independently thereof.

The pointing-tool g (see Figs. 3, 7, 8, 9, and 10) consists of a rod or bar having a pointed end and made in any usual or suitable manner, and preferably made quadrangular in cross-section or any shape other than round, and, as herein shown, two such tools are provided. The tool or tools g , any number being provided as may be desired, are contained in and firmly held by a tool-holder of any suitable construction which is adapted to slide longitudinally. The sliding tool-holder herein shown is composed of a front plate g' , recessed longitudinally from its lower end to a point nearly to its upper end to receive a back plate g^2 , which is made of suitable shape to fit said recess, the upper end of said back plate g^2 abutting against a shoulder g^{20} , formed or provided at the upper end of the recess in the front plate g' , and said back plate g^2 is made in two parts or pieces, to be separately bolted or otherwise secured to the front plate g' . The contiguous faces of the front and back plates are each grooved longitudinally to provide sockets in which the tools are placed, said tools being firmly held in place in said sockets by securing the plates together, and the sockets are made of a shape corresponding to the shape of the tools g , so that said tools are held against rotation. The tools g , when made long enough, will bottom in the sockets, but as they wear away small blocks g^3 will be placed in said sockets, against which the tools will abut, any number of blocks being provided for this purpose.

To remove the tools—as, for instance, for the purpose of sharpening them—it is only necessary to loosen the bolts, and thereby re-

lieve the pressure of the back plate g^2 . The tool-holder $g' g^2$, bearing the pointing-tools g , is contained in and supported by a tool-holder support in such manner as to slide freely in either direction longitudinally for a short distance, and, as herein shown, said tool-holder support is formed or provided at each side or edge with a double bevel to present V-shaped portions $g^4 g^4$, or said tool-holder may be dovetailed to fit correspondingly-shaped recesses formed or provided in the support.

The tool-holder support bearing the sliding tool-holder $g' g^2$ is made of any suitable construction to accommodate the sliding tool-holder and to be adjusted to hold the tools g at any desired angle relative to a horizontal plane, and, as herein shown, said tool-holder support consists of a frame (see Figs. 3, 10, and 14) made open at the bottom and at one side and having a semicircular portion g^6 , and also having at its lower end a downwardly-projecting lip g^7 and at its upper end a circular opening g^8 . To the under side of said frame g^6 two parallel bars $g^9 g^{10}$ are secured, which are located at opposite sides of the frame, said bars being attached at their opposite ends to the opposite ends of the frame g^6 . The bar g^9 is made nearly as long as the frame g^6 , and its lower end bears upon or against the inner side or face of the lip g^7 , and its upper end projects into the opening g^8 , and said bar g^9 is attached to the frame at one end by a bolt or screw 2, passing through the frame and the lower end of the bar, and at the opposite end by a screw 3, passing through the frame and into one side of the bar. The bar g^{10} is similarly constructed and attached to the under side of the frame g^6 in the same manner. The inner or adjacent sides or edges of said bars $g^9 g^{10}$ are formed or provided with grooves from end to end, or substantially so, which are made of suitable shape to receive the V-shaped edges g^4 of the sliding tool-holder, said tool-holder being thereby held in position and guided by said bars $g^9 g^{10}$. The sliding tool-holder $g' g^2$ is placed in position between the bars $g^9 g^{10}$ by inserting it through the opening g^8 in the frame and may be readily removed through said opening at any time. The sliding tool-holder $g' g^2$ has formed or provided on its upper side or face, at its lower end, a projection g^{13} , which is adapted to strike against the inner side of the lip g^7 , said lip thereby serving as a rigid stop to limit the downward movement of the sliding tool-holder. When pointing a stone, a sudden longitudinal thrust is given to the tool, and to obtain such movement the tool-holder, which is normally held pressed against the stop g^7 by a strong spring, is raised against the pressure of said spring and is then released, and a sudden downward thrust thereby given to the tool-holder by means of said spring. One way of carrying out this part of my invention consists in providing a block of rubber g^{14} , which is designed to serve as a spring, and said rubber block g^{14} is held

in a yoke g^{15} , which has formed or provided at its lower end a ring g^{16} , which is seated upon the upper end of the frame just over the opening g^8 , and said ring g^{16} is hinged or otherwise pivotally connected to said frame at g^{17} and is held in fixed position on the frame by means of a screw g^{18} or other suitable fastening. The lower end of the rubber block g^{14} is adapted to bear directly upon the upper end of the sliding tool-holder $g' g^2$ and normally holds said tool-holder against the stop g^7 , and as said tool-holder is raised said rubber block will be further compressed, and the compression of said block g^{14} may be regulated or adjusted by means of an adjusting-screw g^{19} , which passes through the upper end of the yoke g^{15} and bears upon a plate g^{22} , which rests upon the upper end of the rubber block. The yoke g^{15} , bearing the rubber block, is hinged to the plate above the opening g^8 , so that it may be swung to one side, as represented by dotted lines, Fig. 10, to expose said opening and admit of the removal of the sliding tool-holder.

To raise the sliding tool-holder $g' g^2$ against the pressure of the spring g^{14} , a projection g^{25} is formed on the upper side or face of said tool-holder, which is engaged by a short arm h , which serves as an operating-lever, attached to and projecting from a reciprocating shaft h' , and when said arm has been moved by the shaft h' a certain distance it is suddenly released, and the sliding tool-holder is then thrust downward by the spring g^{14} . The opening in one side of the frame is provided for the purpose of admitting the arm h in order that it may engage and operate the sliding tool-holder. The reciprocating shaft h' has projecting from it another arm h^2 , which is engaged by a cam h^3 , secured to a rotating shaft h^4 , held in suitable bearings on the outer cylinder e' , and said cam h^3 is constructed, as shown, to engage and move the arm h^2 , and thereby turn the shaft h' in one direction to in turn raise the sliding tool-holder, and when said tool-holder has been raised to a predetermined elevation the arm h^2 slips off or passes by the projection on the cam and allows the shaft h' to suddenly return to its normal position. The shaft h' is disposed obliquely or diagonally to the outer cylinder e' and is supported on said cylinder e' by a bearing-block h^5 . To vary the stroke of the arm h , and thereby vary the distance that the sliding tool-holder shall be moved to in turn vary the force of the thrust of the pointing-tool, the bearing-block h^5 is made adjustable in a direction outward and from the cam h^3 , so that the arm h^2 will be acted upon more or less by said cam. The bearing-block h^5 is herein shown as having on its rear side a horizontally-disposed dovetailed recess which receives a dovetailed projection h^6 , formed on a bracket h^7 , secured to the cylinder e' , and said bearing-block h^5 is thereby supported, so as to be moved back and forth and in turn move the arm h^2 to-

ward and from the cam h^3 . The bracket h^7 supports a screw h^8 , which turns in said bearing-block h^5 and serves as a means of adjusting it back and forth. The screw h^8 has 5 secured to it at one end a beveled gear h^9 , which is engaged by a beveled gear h^{10} , secured to a shaft h^{12} , having its bearings in a bracket on the cylinder, and a hand-wheel h^{13} is secured to the outer end of said shaft, 10 which serves as a means of turning it, to thereby adjust the bearing-block h^5 . The adjustment of the bearing-block h^5 is sufficient to enable it to be moved to one side far enough to carry the arm h^2 absolutely out of the path 15 of the cam h^3 , and when so adjusted the sliding tool-holder will remain at rest even as the cam continues to revolve. While the means thus described for operating the pointing-tool is simple and efficient, I do not desire to 20 limit my invention to the employment of the specific means shown, as it is obvious that other means may be provided capable of accomplishing the same results which come within the spirit and scope of this invention.

25 The frame of the tool-holder support is secured to an arm or bracket i , projecting from the cylinder e' , by bolts 4, which pass through slots i' in said arm and into and through the frame, and said arm i is curved to receive 30 the semicircular portion g^6 of the frame, provision being thereby made for adjustment of said frame relatively to the arm in a circular direction or on a horizontal axis, to thereby vary the angle of the tool-holder and tools 35 carried by it. The semicircular formation g^6 of the frame is employed for the particular purpose of providing for such adjustment of the tool-holder, yet it is obvious that this result may be otherwise accomplished without 40 departing from this invention.

The shaft h^4 , bearing the cam h^3 , is adapted to be continuously rotated regardless of the position of the carriage bearing the turret, and to accomplish this result a toothed gear 45 j is secured to the shaft h^4 —as, for instance, to its lower end, which is engaged by an idle toothed gear j' , supported by a stud projecting from the bottom plate e^8 of the cylinder e' , and said idle gear j' is engaged and driven 50 by a toothed gear j^2 , secured to the lower end of a shaft j^3 , which extends up through the center of the cylinder e' , passing through the bottom plate e^8 and boss or projection e^4 and through the plates e^5 and e^{10} , and said upper shaft j^3 has secured to its upper end a belt-pulley j^4 , which is at all times in engagement with the belt b^9 even as the carriage is moved from end to end of the machine, and as said shaft j^3 is thus continuously revolved 55 the shaft h^4 will also be continuously revolved by means of the gearing thus described.

60 By referring to Fig. 1 it will be seen that the belt b^9 passes around one side of the belt-pulley d^9 and around the opposite side of the belt-pulley j^4 and also around one side of an idle belt-pulley k , supported on the carriage,

and by thus arranging said pulleys relatively to the belt it will be seen that the carriage may be moved along in either direction and 70 said pulleys will at all times remain in engagement with said belt.

75 By disposing the shaft j^3 , which serves as the main operating-shaft for the tool-holder, at or coincident with the axis of the tool-carrier and by connecting the shaft h^4 with said shaft j^3 it will be seen that the turret may be adjusted on its vertical axis to any different position without rendering the parts inoperative. It will be observed that the toothed 80 gears j and j' travel around the toothed gear j^2 —i. e., they have a planetary movement relative thereto.

85 One of the particular advantages of having the turret adjustable on its vertical axis and supported by a movable carriage is to enable the pointing-tools to always cut inwardly from the edge of the stone—a result which in practice prevents chipping off small pieces from the edge of the stone.

90 Referring to Fig. 15, q represents the top surface of a stone, and q' the position of the pointing-tool when starting to cut the stone, the cut being made from the edge inwardly. While the tool is held in this oblique position 95 and vibrated, the tool-carriage will remain at rest and the truck will be moved transversely, and as the stone is carried along by the truck one edge is cut inward for a short distance, but before said stone passes entirely beneath the tool the tool is swung on its vertical axis to cut around the corner and is soon brought 100 into the position marked q^2 , and then the truck is stopped and the tool-carriage travels from left to right and another edge is cut inward for a short distance but before the tool-carriage carries the tool by or beyond the stone 105 the tool is again swung on its vertical axis into the position marked q^3 , the tool-carriage stopped, and the truck started, and as the truck 110 returns to its starting-point another edge of the stone is cut, but before the stone is carried entirely beneath the tool said tool is again swung into the position marked q^4 and the truck stopped and the tool-carriage started, and by thus alternately operating the 115 truck and tool-carriage and swinging the tool on its vertical axis the stone will be cut inward from the edge as far as desired. A single cut may be made inward from the edge entirely 120 around the stone or as many cuts as desired, although instead of cutting the entire top surface in this manner the middle portion within certain prescribed limits may be cut in parallel lines if desired, yet in ordinary working 125 of the machine no particular advantages are gained by thus changing the operation. As the stone is cut inwardly from the edge all around, it will be seen that the turret bearing the cutting-tool makes a complete revolution 130 and that the said tool occupies different positions in a complete cycle as the turret is thus revolved.

135 The bushing-tool which will be employed

in connection with my machine may be of any usual or suitable construction; but the particular construction herein shown possesses certain novel features, and it consists, essentially, of a number of flat plates m , formed with cutting edges and disposed in a gang in a recessed head, and said head is composed of a base m' , having side pieces and end pieces which present a rectangular recess in which the plates m are placed, and one of the end pieces, as m^2 , is hinged at m^3 to the base in order that it may be moved outwardly for the purpose of removing the plates whenever desired, and such hinged end piece m^2 projects beyond the adjoining sides of the head, and a loop-like or U-shaped strap m^5 passes around said head, the ends of which project through holes in the hinged piece m^2 , and said projecting ends receive upon them nuts m^4 . Thus the plates m are held clamped in position by the strap, but may be removed by loosening said nuts m^4 . The head carrying the plates is secured to the lower end of an operating rod or bar n , which is splined into a sleeve or bushing n' , so as to slide freely longitudinally in either direction, but is prevented from rotation within the sleeve or bushing, and said bar n and head carried by it serves as and constitutes the tool-holder. The sleeve or bushing n' is contained within and supported by a frame n^2 , which is bolted or otherwise secured to the cylinder e' , and said sleeve and frame serve as the tool-holder support.

It is designed and intended that the bushing-tool shall have a sudden thrust, like the pointing-tool heretofore described, and to accomplish this result the upper end of the rod or bar n has secured to it a circular flange or disk n^3 , the under side of which is engaged by one end of a lever n^4 , which projects through an opening n^5 in the frame n^2 , so as to occupy such position beneath the flange, and said lever n^4 is pivoted at n^6 to a block n^7 at a point intermediate its length, and its opposite end is engaged by a cam n^8 , secured to the rotating shaft h^4 . As the cam n^8 revolves the lever n^4 will be operated to repeatedly raise the rod or bar n . A rubber block n^9 is provided which bears upon a plate n^{10} , resting upon the upper end of the rod or bar n , and said rubber block n^9 is held more or less compressed and its pressure regulated by an adjusting-screw n^{12} , which passes through the upper end of a yoke n^{13} , formed or provided at the upper end of the frame n^2 . As the lever n^4 is raised by the cam n^8 the rod or bar n will be raised against the pressure of the rubber block n^9 , and when said lever is released a sudden thrust is given to the rod n by the spring n^9 . The block n^7 , to which the lever n^4 is pivoted, is mounted in a support n^{15} , formed or provided with a guideway whereby said block may be caused to occupy different elevations, and said block is supported upon or by an adjusting-screw n^{16} , whereby it may be held in different elevations. As the position

of the block n^7 is varied the lever n^4 will be moved toward and from the cam n^8 , so that the force of the thrust given to the rod n may be more or less, and when said block is adjusted to occupy its lowermost position said lever n^4 will be moved out of the path of the cam n^8 , and at such time the bushing-tool will remain at rest as the cam n^8 revolves. 75

The bushing-tool may be adjusted on its vertical axis to occupy any position desired relative thereto, and to accomplish this result the sleeve or bushing n' is formed or provided at its lower end with a worm-wheel o , 80 which is engaged by a worm o' , secured to a shaft o^2 , having its bearings in a bracket o^3 , secured to the cylinder e' , and a hand-wheel o^4 is secured to said shaft o^3 , which serves as a means of turning it. The frame n^2 (see 85 Figs. 3, 6, and 13) projects from a circular plate n^{20} , which is formed or provided with two curved slots n^{21} , through which bolts n^{22} pass, which enter a boss n^{23} on the cylinder e' , and said slots permit turning the plate n^{20} , 90 so that the bushing-tool may be swung to one side by turning it on a horizontal axis into out-of-use position.

In order that the bushing-tool may be adapted for cutting an irregular surface, I 95 have provided blocks, such as m^{50} , which may be placed in the holder, as shown in Figs. 6 and 11, which act to hold the plates, with their cutting edges, in different relative planes. 100

It will be seen that the two different tools herein described may be operated independently or at the same time, as may be desired, according to the work being done.

As an illustration of the work to be done 105 the pointing-tool may pass once over the surface of the stone, and then in passing over the stone the second time the pointing-tool may be again used, followed by the bushing-tool, both tools operating at the same time, 110 and finally in passing over the stone the third time the bushing-tool alone may be used, thus in three operations the stone will be twice acted upon by the pointing-tool and also twice acted upon by the bushing-tool. 115

I claim—

1. In a stone-dressing machine, the combination of a turret adapted to turn on a vertical axis, a tool carried by said turret, a cam also carried by said turret for raising said tool, a spring for suddenly returning said tool when the cam releases it, a driving-shaft for said cam which passes through said turret, means for rotating said driving-shaft, and means for adjusting said turret about its 120 vertical axis while said driving-shaft is operating, substantially as described.

2. In a stone-dressing machine, the combination of a turret adapted to turn on a vertical axis, a tool carried by said turret, a cam also carried by said turret for raising said tool, a spring for suddenly returning said tool when the cam releases it, a driving-shaft for said cam which passes through said tur- 130

ret, means for adjusting said turret about its vertical axis, means for adjusting said turret to different elevations, and means for rotating said driving-shaft while the turret is being adjusted, substantially as described.

3. In a stone-dressing machine, the combination of a carriage, means for moving it back and forth, a turret borne by said carriage adapted to turn on a vertical axis a complete rotation, a tool-holder carried by said turret, a tool held by said tool-holder at an oblique angle to a horizontal plane, a cam carried by said turret for raising the tool, a spring for suddenly returning the tool when the cam releases it, a driving-shaft for said cam, and means for adjusting said turret about its vertical axis whereby the tool may occupy a position at an oblique angle to the movement of the carriage and also any other position in the cycle in which said turret revolves, substantially as described.

4. In a stone-dressing machine, the combination of a carriage, means for moving it back and forth, a turret borne by said carriage adapted to turn on a vertical axis a complete rotation, a tool-holder carried by said turret, a tool held by said tool-holder at an oblique angle to a horizontal plane, a cam carried by the turret for raising the tool, a spring for suddenly returning the tool when the cam releases it, a driving-shaft for said cam, means for adjusting said turret about its vertical axis whereby the tool may occupy a position at an oblique angle to the movement of the carriage and also any other position in the cycle in which said turret revolves, and means for adjusting said turret to different elevations, substantially as described.

5. In a stone-dressing machine, the combination of a truck bearing a stone to be operated upon, means for moving it back and forth, a turret adapted to turn on a vertical axis a complete rotation, a tool-holder carried by said turret, a tool held by said tool-holder at an oblique angle to a horizontal plane, a cam carried by the turret for raising the tool, a spring for suddenly returning the tool when the cam releases it, a driving-shaft for said cam, and means for adjusting said turret about its vertical axis whereby the tool may occupy a position at an oblique angle to the movement of the truck and also any other position in the cycle in which said turret revolves, substantially as described.

55 6. In a stone-dressing machine, the combination of a truck bearing a stone to be operated upon, means for moving it back and forth, a turret adapted to turn on a vertical axis a complete rotation, a tool-holder carried by said turret, a tool held by said tool-holder at an oblique angle to a horizontal plane, a cam carried by the turret for raising the tool, a spring for suddenly returning the tool when the cam releases it, a driving-shaft for said cam, means for adjusting said turret about its vertical axis whereby the tool may occupy a position at an oblique angle to the

movement of the truck and also any other position in the cycle in which said turret revolves and means for adjusting said turret to different elevations, substantially as described.

7. In a stone-dressing machine, the combination of a carriage, means for moving it back and forth, a turret borne by said carriage adapted to turn on a vertical axis a complete rotation, a tool-holder carried by said turret, a tool held by said tool-holder at an oblique angle to a horizontal plane, means for vibrating said tool, means for adjusting said turret about its vertical axis whereby the tool may occupy a position at an oblique angle to the movement of the carriage and also any other position in the cycle in which said turret revolves, a driving-shaft passing through said turret which serves as a coöperative part of the means for vibrating said tool, driving mechanism in continuous engagement with which said driving-shaft is adapted to be held as the tool-carriage travels back and forth and also as the turret is adjusted on its vertical axis, a truck bearing the stone to be operated upon and means for moving it back and forth at right angles to the movement of said tool-carriage, substantially as described.

8. In a stone-dressing machine, the combination of a carriage, means for moving it back and forth, a turret borne by said carriage adapted to turn on a vertical axis a complete rotation, a tool-holder carried by said turret, a tool held by said tool-holder at an oblique angle to a horizontal plane, means for vibrating said tool, means for adjusting said turret about its vertical axis whereby the tool may occupy a position at an oblique angle to the movement of the carriage and also any other position in the cycle in which said turret revolves, means for adjusting said turret to different elevations, a truck bearing the stone to be operated upon and means for moving said truck back and forth at right angles to the movement of said tool-carriage, substantially as described.

9. In a stone-dressing machine, the combination of a carriage, means for moving it back and forth, a turret borne by said carriage adapted to turn on a vertical axis a complete rotation, a tool-holder carried by said turret, a tool held by said tool-holder at an oblique angle to a horizontal plane, means for vibrating said tool, means for adjusting said turret about its vertical axis whereby the tool may occupy a position at an oblique angle to the movement of the carriage and also any other position in the cycle in which the turret revolves, means for adjusting said turret to different elevations, a driving-shaft passing through said turret which serves as a coöperative part of the means for vibrating said tool, driving mechanism in continuous engagement with which said driving-shaft is adapted to be held as the carriage travels back and forth and also as the turret is ad-

justed on its vertical axis and to different elevations, a truck bearing the stone to be operated upon and means for moving said truck back and forth at right angles to the movement of the carriage, substantially as described.

10. In a stone-dressing machine, the combination of a tool, a tool-holder therefor, a support for holding said tool-holder with its tool disposed at an oblique angle to a horizontal plane, an adjusting device for said support whereby said obliquity of the tool may be varied, means for vibrating said tool, a turret adapted to turn on a vertical axis a complete rotation which carries said tool-support and the means for vibrating the tool whereby said turret may be turned while the tool is vibrating, means for adjusting said turret about its vertical axis whereby the oblique cutting-tool may be held in any position in the cycle in which said turret moves, a carriage bearing said turret, means for moving it back and forth while the tool is vibrating, a truck bearing the stone to be operated upon and means for moving it back and forth at right angles to the movement of said carriage, substantially as described.

11. In a stone-dressing machine, the combination of a tool, a tool-holder therefor, a support for said tool-holder adapted to hold the tool at an oblique angle to a horizontal plane, an adjusting device for said support whereby said obliquity of the tool may be varied, a cam for raising said tool, a spring for returning it when said cam releases it, a turret adapted to turn on a vertical axis a complete rotation which carries said tool-support and the operating device for the tool, means for adjusting said turret about its vertical axis whereby the tool may occupy any position in the cycle in which said turret moves, a carriage bearing said turret, and means for moving said carriage back and forth, substantially as described.

12. In a stone-dressing machine, a turret adapted to turn on a vertical axis, a vibrating tool carried by said turret, a stop for limiting the downward thrust of said tool, a spring for normally holding said tool in its lowermost position resisted by said stop, a cam for raising said tool against the action of said spring, which latter suddenly returns the tool when the cam releases it, means for rotating said cam, and means for adjusting the turret on its vertical axis, substantially as described.

13. In a stone-dressing machine, a turret adapted to turn on a vertical axis a complete rotation, a vibrating tool carried by said tur-

ret, a tool-holder for holding said tool at an oblique angle to a horizontal plane, a stop for limiting the downward thrust of the tool, a spring for normally holding said tool in its lowermost position resisted by said stop, a cam for raising said tool against the action of said spring, which latter suddenly returns the tool when the cam releases it, means for rotating said cam, and means for adjusting said turret on its vertical axis whereby the tool carried by it may occupy any position in the cycle in which said turret revolves, substantially as described.

14. In a stone-dressing machine, a turret adapted to turn on a vertical axis a complete rotation, a vibrating tool carried by said turret, a tool-holder for holding said tool at an oblique angle to a horizontal plane, a stop for limiting the downward thrust of the tool, a spring for normally holding said tool in its lowermost position resisted by said stop, a cam for raising said tool against the action of said spring, which latter suddenly returns the tool when the cam releases it, means for rotating said cam, means for adjusting said turret on its vertical axis whereby the tool carried by it may occupy any position in the cycle in which said turret revolves, a carriage bearing said turret and means for moving it back and forth, substantially as described.

15. In a stone-dressing machine, a turret adapted to turn on a vertical axis a complete rotation, a vibrating tool carried by said turret, a tool-holder for holding said tool at an oblique angle to a horizontal plane, a stop for limiting the downward thrust of the tool, a spring for normally holding said tool in its lowermost position resisted by said stop, a cam for raising said tool against the action of said spring, which latter suddenly returns the tool when the cam releases it, means for rotating said cam, means for adjusting said turret on its vertical axis whereby the tool carried by it may occupy any position in the cycle in which said turret revolves, a carriage bearing said turret and means for moving it back and forth, substantially as described.

In testimony whereof I have signed my name to this specification in the presence of two subscribing witnesses.

ALBERT F. JONES.
